[57] CLAIM

The ornamental design for a guide for centering a boat

being drawn onto a boat trailer, as shown and described.

DESCRIPTION

FIG. 1 is a perspective view of a guide for centering a boat being drawn onto a boat trailer, showing my new design, and illustrating the length-adjustable pivoted arm at approximately mid-length position;

FIG. 2 is a bottom plan view thereof;

FIG. 3 is a top plan view thereof;

FIG. 4 is a rear elevational view thereof, showing the pivoted arm and roller in inclined attitude resulting from engagement with the hull of a boat being loaded onto a boat trailer on which is mounted a spaced pair of the guides arranged in mirror symmetry on opposite sides of the trailer;

FIG. 5 is an elevational view of the outer side thereof; FIG. 6 is a view similar to that of FIG. 4 but showing the pivoted arm and roller in the spring-urged vertical attitude assumed by the guide when it is not deflected by a boat hull, the opposite, or front, side being a mirror image thereof; and,

FIG. 7 is an elevational view of the inner side thereof. The broken line in FIG. 4 represents the fragmentary outline of boat hull in engagement with the guide and forms no part of the present design.

FIG. 1.

FIG. 2.

FIG. 3.

FIG. 4.

FIG. 5.

FIG. 6.

FIG. 7.
